DESIGN FOR A SETTEE FRAME OR SIMILAR ARTICLE

Sylvester M. Berth, Chicago, Ill., assignor to Anton Szumny, doing business as Anton
Szumny and Sons, Chicago, Ill.

Application August 30, 1935, Serial No. 58,373

Term of patent 3½ years

To all whom it may concern:

Be it known that I, Sylvester M. Berth, a citizen of the United States, residing at Chicago, Cook County, Illinois, have invented a new, original, and ornamental Design for a Settee Frame or Similar Article, of which the following is a specification, reference being had to the accompanying drawing, forming a part thereof.

The figure is a perspective view of a settee frame or similar article, showing my design, the dominant features thereof being shown in full lines.

I claim:

The ornamental design for a settee frame or similar article, as shown and described.

In witness whereof, I hereunto subscribe my name this day of August 21, 1935.

SYLVESTER M. BERTH.
